NILS WENER, OF STOCKHOLM, SWEDEN, ASSIGNOR TO SVENSKA AKTIEBOLAGET MONO.

PUMPING DEVICE.

1,352,856.

Specification of Letters Patent. Patented Sept. 14, 1920.

Application filed June 17, 1918. Serial No. 240,541.

To all whom it may concern:

Be it known that I, NILS WENER, subject of the King of Sweden, residing at 11 Uppsalagatan, Stockholm, Sweden, have invented 5 certain new and useful Improvements in Pumping Devices, of which the following is a specification.

The present invention relates to a pumping device with an oscillating liquid-piston, 10 which is especially suitable for the operation of gas-analyzing apparatus.

In German patent No. 226,542 there is described a liquid-piston pump, adapted to operate by either pressure or suction, and 15 comprising two receptacles, communicating with each other, and a return pipe for the pumping liquid, arranged in a branch from either the outlet or inlet pipe of the pressure exhaust or inlet pipe. If this pump 20 is, for instance, employed as a gas-analyzing apparatus, by means of which two different analyses are alternately performed, several difficulties will arise. In order to avoid these difficulties in a simple manner, 25 the pump, according to the present invention, is constructed as a duplex pump, triplex pump, and so forth, in such a manner that at each pumping stroke a small quantity of the pump liquid is conducted from 30 one pump to another by the return pipe leading from one pump to the other. The overflowing quantity of liquid is thereby so large that that pump, from which this quantity flows, can no longer work, while that 35 pump which receives this quantity will be put into action.

The nature of the invention disclosed in the above-mentioned German patent may be explained schematically in the following 40 manner: If A¹, B¹ indicate the two receptacles of one pump, A², B² the receptacles of another pump, and A³, B³ the same of a third pump, the three return pipes lead 45 from A¹ to B², from A² to B³ and from A³ to B¹. The arrangement for a duplex pump or for pumps provided with more than 50 three pairs of receptacles is similar. The pumps can, however, also be connected in another manner, namely, by means of an overflow pipe, through which the said small quantity of liquid will flow at each stroke.

In such an arrangement the pumps will be operated automatically and alternately, so that the measuring receptacles of the 55 analyzing apparatuses connected with the

pumps also may receive the action as desired.

Some embodiments of the invention suitable for a gas-analyzing apparatus are schematically shown in the accompanying 60 drawing,—

Figure 1 showing diagrammatically in elevation one form of such apparatus, and

Figs. 2 and 3 showing in similar view two other forms.

In Fig. 1, a¹ a² indicate the supply piping for the pressure agent, as, for instance, compressed air, driving the pumps, the air being supplied to both pipes at substantially equal pressure. P¹ and P² are the two 70 pumps, which are constructed in approximate accordance with the German patent No. 226,542, with the exception, however, that the return pipes are arranged in another manner. Each pump comprises an 75 inner receptacle b¹ or b² which, partly filled with mercury, are connected with each other by the piping c¹ and c². In the receptacles b¹ and b² the smaller receptacles d¹ and d² are arranged, which, through an opening in 80 the side wall, communicate with the receptacles b¹ and b². Into these receptacles d¹ and d², which are connected by means of the pipings a¹ and a², the stand-pipes e¹ and e² reach almost to the bottom. The upper 85 ends of the stand-pipes open into receptacles f¹ and f² and from these receptacles the return pipes g¹ and g² are conducted to the pipings c¹ and c².

To these pipings c¹ and c² the common 90 stand-pipes and measuring receptacles are connected in a manner known in gas-analyzing apparatus. The latter are, as well as the supply and exhaust pipings of the measuring receptacles M¹ and M², schematically 95 shown in the drawing.

The action of receptacles M¹ and M² is similar to that of the like device in U. S. Patent No. 947,533. When liquid from the pump rises in the said receptacles, the gas 100 is pressed therefrom through the pipes leading to the right, from the liquid seals above the receptacles. When, on the other hand, the liquid falls in said receptacles, fresh gas is sucked in through the pipes coming from the left and emptying in said water seals. This is the usual action in most gas-analyzing 105 apparatuses, where a falling and rising liquid is used for filling and emptying the first measuring receptacles.

The mode of operation of the device is as follows: Assume that one of the receptacles d^1 or d^2 (Fig. 1) contains so little mercury that it cannot be put in action. d^2 may, for example, contain such a small quantity of mercury that the lower end of the stand-pipe e^2 will not be submerged, and consequently, the air issuing from pipe a will escape through e^2 , f^2 to atmosphere without exerting pressure downwardly on the surface of mercury in b^2 . The second receptacle is assumed to be filled with mercury to a normal extent, that is, to a depth at which the lower end of pipe e^1 will be submerged. 10

15 The pressure-agent flows constantly in the piping a^1 and a^2 , but through a^2 , d^2 and e^2 flows off into the open air and therefore exercises no action upon the pumping device. In the receptacle d^1 , on the contrary, 20 the pressure-agent presses upon the surface of the mercury in b^1 and d^1 , which communicate with each other, so that the mercury will be partially forced out of the receptacle b^1 into the piping c^1 . The columns of liquid in pipes g^2 , h^1 , p^1 , o^1 , connected with this piping c^1 , will therefore rise. The gas mixture in M^1 , which is to be 25 analyzed, will be forced out through the trap or valve m^1 and pipe n^1 to the analyzing receptacle (not shown). While the action just described is taking place, liquid from d^1 rises in the stand-pipe e^1 and is eventually forced out through the upper 30 end of e^1 into f^1 . Thereupon, a reversal of the action takes place. The mercury, forced 35 up through e^1 , will find its way from f^1 through g^1 to the other side of the system, comprising c^2 , b^2 , o^2 , p^2 , h^2 . The spaces above the mercury in the two receptacles b^1 40 and d^1 will now be in communication with the atmosphere through the pipe e^1 ; the pressure will drop to that of the atmosphere and the liquid will sink in all pipes and receptacles which are connected with the piping c^1 , flowing back to the receptacle b^1 . As 45 the column of mercury in pipe c^1 and measuring receptacle M^1 falls, a quantity of gas will be drawn into M^1 through pipe K^1 , to be expelled through n^1 when the column 50 next rises. As a small quantity of mercury has been transferred from the pump P^1 to the pump P^2 , the quantity of mercury in b^1 can no longer reach the opening in the side wall of the receptacle d^1 , and therefore 55 there will be an insufficient quantity of mercury in d^1 to submerge the lower end of the pipe e^1 , hence the pressure-agent issuing from a^1 will merely pass to atmosphere through e^1 , f^1 , and pump P^1 will be inactive 60 for the time being.

In the meantime, the pump P^2 has been rendered active because of the small quantity of mercury transferred from P^1 to P^2 , the surface of the mercury in the receptacle b^2 having been thereby raised so that

mercury may flow in through the opening in the side wall of the receptacle d^2 . The quantity of liquid flowing in will form a liquid seal for the lower end of the stand-pipe e^2 , and now the pump P^2 is ready for 70 action and will work in the manner described above with reference to the pump P^1 . When the action of the pump P^2 has been completed, a quantity of liquid will have flowed through e^2 and f^2 back to the 75 piping c^2 , so that the receptacle b^2 again holds the greater quantity of liquid and the pump P^1 is in action.

In this way the two pumps P^1 and P^2 will be alternately operated; when P^1 is working, P^2 is out of action, and vice versa. The result is, of course, that the measuring receptacles M^1 and M^2 are alternately emptied and the gas tests disclosed therein will be alternately expelled from the receptacles 85 M^1 and M^2 in order to effect the analysis.

In the device above described, a further inconvenience has appeared, as it is not possible to build the different receptacles and pipings in such a manner that the quantity of the liquid transferred from P^1 to P^2 will always exactly correspond to the amount transferred from P^2 to P^1 . If a difference does exist, the discrepancy will not be equalized, but will always go in one 95 direction, so that eventually the pumping device will fail to function in the manner desired.

This inconvenience can be easily eliminated by having the pipings c^1 and c^2 connected with two stand-pipes, communicating with each other by an overflow piping. This piping is V-formed and the point of the piping arranged at such a height that during normal working of the pumps, no liquid 105 is transmitted from one pipe system to another. Should, however, one pump deliver more liquid than it holds back, an equalization then will take place through the overflow piping.

The alternating work of the two pumps is so arranged that a small quantity of pump liquid is at every second stroke brought to pass from the pump system b^1 , c^1 , d^1 , e^1 , f^1 , g^1 to the other system b^2 , b^2 , d^2 , e^2 , f^2 , g^2 , and at every second stroke the said small liquid quantity is brought to flow from the last-named system back to the first-named system. Now, it can of course occur that this small liquid quantity is not the 110 same at every stroke; the fault could be such that always the quantity from the system 1 to the system 2 is a little greater than the quantity from the system 2 to the system 1. Then, of course, after only a few 125 strokes, the device would cease to work. In order to avoid this, an overflow is arranged, which is so situated that when normal conditions occur, the top point of the said overflow is just reached by the liquid when it 130

turns from the rising movement to the falling one. Should, however, at any stroke, too great a quantity of liquid have flowed over from one system to the other, then a correction is immediately made at the falling and rising operation, as then the surplus can flow back again from h^1 to h^2 , or vice versa, through the pipe i .

Fig. 2 shows an embodiment fundamentally corresponding to Fig. 1. The difference principally consists in that the two receptacles of each pump are not directly connected with each other. The two pipes g^1 and g^2 do not in this embodiment connect with the pipings c^2 or c^1 , but with the receptacles d^2 or d^1 . In this embodiment the branches a^3 or a^4 from the pipings a^1 or a^2 connect with the receptacles b^1 and b^2 .

The pipes g^1 and g^2 must in this embodiment be U-formed, so that there will always be a liquid seal in each of the pipes.

Another embodiment is shown in Fig. 3. Here the small quantity of liquid flowing from one pump to another flows through the piping i . Each of the return pipes g^1 and g^2 is conducted back to the large receptacle of its own pump, as in the German patent No. 226,542. g^1 terminates in c^1 , and g^2 in c^2 . In this embodiment the apex of the piping i must lie a little lower than in the embodiment according to Fig. 1. The action of the pump is the same as in Figs. 1 and 2, and also like them, in that a small quantity of liquid at the next stroke flows from one pump to another, and vice versa, so that always only one pump will be put into action.

The embodiment according to Fig. 2 can of course be constructed in such a manner that the two receptacles d^1 and d^2 will be 40 separated from the receptacles b^1 and b^2 .

Claims.

1. A pumping device having pumps which work alternately and are provided with oscillating liquid-pistons and two receptacles 45 connected with each other, having each connected to deliver at each stroke a small quantity of the pump liquid to the other pump.

2. An embodiment of a pumping device as 50 claimed in claim 1, having return pipes between the two receptacles of each pump, each return pipe from one receptacle of one pump conducting to the second receptacle of the other pump.

3. An embodiment of a pumping device as claimed in claim 1, having one receptacle of each pump connected with the corresponding receptacle of another pump, by means of a return pipe, through which the 60 small quantity of the pump liquid can overflow.

4. In an embodiment as claimed in claim 3, the return pipes provided with liquid seals.

5. In an embodiment as claimed in claim 1, the arrangement of an overflow piping between the different pumps.

In testimony whereof I affix my signature in presence of two witnesses.

NILS WENER.
